(57) **CLAIM**

The ornamental design for a latch of cable connector for portable media player, as shown and described.

DESCRIPTION

FIG. 1 is a top plan view of a latch of cable connector for portable media player showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top, front and left side perspective view thereof, in use condition, and on a reduced scale; and,

FIG. 8 is a top, front and left side perspective view thereof.

The broken line of the environment is included to show unclaimed subject matter only and forms no part of the claimed design.

Our latch of cable connector for portable media player is characterized by the features as shown in the drawings.
